FUEL BURNER

Henri G. Chatain, Erie, Pa., assignor to Northern Laboratories, Inc., Cleveland, Ohio, a corporation of Ohio

Application January 10, 1933, Serial No. 650,978

3 Claims. (Cl. 110—46)

This invention relates to fuel burners or furnaces and their operation, wherein combustion is had of solid fuels such as coal, coke and the like, in sizes too great to permit combustion in suspension in a stream of air as is sometimes the practice with so-called pulverized fuels.

The principal general object of the invention is to provide for combustion of improved characteristics, rapid, complete, and at a maximum temperature. Another object is to provide an intimate commingling between the fuel particles and the gas, usually air, for their combustion, during the combustion period, without increasing the volume of air supplied to the fuel beyond that necessary for complete combustion.

More particularly this is accomplished by increasing the relative velocity between the fuel and its air without increasing the volume of air. The invention thus contemplates rapid motion of the fuel in a controlled volume of air during combustion so that the air has a brushing effect upon the fuel, by which combustion is accelerated.

The exact nature of this invention together with further objects and advantages thereof will be apparent from the following description taken in connection with the accompanying drawing, which is a conventionalized showing illustrative of the principles of the invention.

With reference now to the drawing, 1 is the fuel carrying bed, generally of the conical form indicated, arranged about an upright axis with its small end lowermost, and having its inner surface lined with fire brick 2 or like heat resistant material. The upper, large end, of the bed may be flared outwardly as indicated at 3, and its lower, small, end has an opening as at 4. The bed is arranged for rotation upon the axis of its conical configuration. For this purpose it has a rigidly associated sleeve 5 carried in bearings 6 and 7, and motor means 8 is arranged to drive the sleeve 5 as by the belt 9 running over the pulleys indicated.

Means are provided for feeding fuel into the hollow of the bed by way of the opening 4. For this purpose a tube 10 is led to the small end of the bed, upwardly through the hollow of the driving sleeve 5 of the latter, and means are provided for forcing fuel into the opposite end of the tube. Such means are here conventionally shown as the usual ram 11 operated by motor 12 through gearing 13 for intermittent delivery from the hopper 14 into the tube 10.

Air for combustion is delivered to the hollow of the fuel bed as by a pipe 15 having its mouth 16 arranged centrally of the bed opposite the fuel opening 4. A deflector plate 17 may be associated

with the mouth 16 as by legs 18, whereby air delivered through the pipe 15 will be directed radially outwardly as it leaves the mouth 16. It will be appreciated that the pipe 15 may be served by a blower, and at any rate the delivery of air through the pipe is controlled, as conventionally indicated by valve 19.

An ignition device conventionally indicated at 20 may be associated with the plate 17.

The fuel bed and immediately associated parts 10 are enclosed in a housing 21, preferably cylindrical. The housing includes a transverse partition 22 below the fuel bed and shown as rigidly associated with the base casting 23 which carries the fuel bed bearings 6 and 7.

This partition has an opening 24 and an ash chute 25 is arranged as indicated to deliver from the opening to the outside of the housing 21. A number of radially extending paddles or scraper arms 26 overlying the partition 22 are rigidly associated with a collar 27, rotatably mounted upon a cylindrical bearing 28 of the base casting 23. This collar 27 carries a ring gear 29 with which a pinion 30 is mounted for driving engagement. The pinion shaft 31 extends out beyond the wall of the housing 21 and there carries a crank 32. Obviously the arrangement is such that operation of the crank 32 will cause rotation of the scrapers 26 whereby ashes collected on the floor of the partition 22 will be delivered into the chute 25.

The housing 21 may be provided with a reinforcing member 33 immediately above the fuel bed and serving as a baffle adjacent the peripheral extremity of the latter.

It will be appreciated that the housing 21, above the partition shown has an associated heat transfer device, and that means are provided for disposition of the gaseous products of combustion. These are not shown, as being well known in the art and forming no part of the present invention.

Operation will be as follows, assuming the furnace in operation, the fuel bed being rotated by the motor 8, the fuel being delivered to the bed by operation of the fuel feeding apparatus, and air being delivered to the fuel by the pipe 15.

The rate of fuel delivery is of course adjusted to the capacity demand of the burner. The fuel is delivered from the hopper 14 to the bed by way of the opening 4 in the latter which is served by the tube 10. The fuel as it passes through the opening 4 and into the fuel bed, is of course cold.

The bed is rotated at such a speed that the fuel therein is caused to move slowly upwardly upon the lining 2 of the bed by centrifugal force.

Gravity having a constant effect on the fuel tending to move it downwardly, and the centrifugal force being variable by varying the speed of bed rotation, the rate of upward travel of the fuel 5 may be nicely controlled by varying the speed of the motor 8. Also, the centrifugal force maintains the fuel spread evenly upon the lining 2 so that as the fuel progresses upwardly past the opening 4 it shortly assumes an annular form, 10 generally conical as indicated.

The pipe 15 delivers air into the hollow and 15 near the apex of this cone of fuel, the pipe being cooled by the air flowing through it, the temperature of which air is correspondingly raised. The air flows onto the fuel radially from the cone axis. Thence as it strikes the fuel it must rise 20 generally parallel with the axis, and eventually it leaves the cone and is conducted away and to a stack as in the usual manner of disposal of products of combustion, the oxygen of the air being substantially wholly combined with the fuel before emerging from the cone, so that analysis of the gaseous discharge of the cone should disclose 25 substantially no oxygen. The volume of air delivered through the pipe is controlled as by the valve 19 or equivalent means to this end.

As the fuel rises on the bed the centrifugal force upon it becomes greater, since its radius from the axis is increased. Also the bed area 30 increases with its elevation so that the fuel bed becomes thinner as it approaches the upper and outer extremity of the cone, all as indicated in the drawing. Also as the fuel rises its combustion takes place and it is gradually reduced to 35 ash. Ultimately this ash reaches the upper extremity of the cone whence it is thrown off and drops upon the partition 22. Thereafter it may be removed by way of the chute 25 by manipulation of the crank 32.

It is to be observed that the fuel during its combustion has rapid absolute motion in a convolute path of relatively minute pitch, since its 40 rotating component of motion is very much greater than its upwardly and outwardly advancing component of motion. The air on the contrary is blown radially against the fuel. Consequently 45 during combustion the fuel has high velocity relative to the air, with consequent brushing characteristic of the effect of the air upon the fuel. This brushing action is comparatively independent of the volume of air, since it is the result of absolute fuel motion as much as of absolute air motion, so that chemically, substantially perfect 50 combustion may be had without the excess air heretofore found necessary for a brushing action. The brushing action of course comprises a flow of the air against the fuel, and effects an intimate commingling of the air and fuel, the air having high turbulence relative to the fuel particles so that combustion is very rapid. This high 55 rate of combustion obviously produces a maximum temperature.

The fuel-carrying bed being imperforate and lined with suitable material, there is no danger

of burning out the bed, notwithstanding the extreme temperatures attained. The usual problem of clinkering is entirely eliminated. If clinkers form they are rapidly removed from the surrounding fuel because of their higher specific gravity. They simply advance upwardly and from the bed ahead of the fuel from which they originate. The baffle 33 serves to prevent entrainment of solid particles in the flue gases. 5

In general, regardless of the size of a fuel particle, it is burned in this device with characteristics comparable to the usual burning of pulverized fuel entrained in a stream of air. Indeed the combustion characteristics in this device are superior, in that the fuel and air are positively caused to have great relative motion during combustion, yet without excess air being employed. 10

Obviously the embodiment here shown of the device is illustrative only. The conical pitch of the fuel bed may depend somewhat upon the speed range through which it is to have operation, the specific gravities and sizes of fuels to be handled, the amount of clinker, weight of ash, etc. There will always be an annular zone of fuel having maximum rate of combustion and by varying the pitch of this or another zone, the rate of advance of fuel over such zone may be increased or decreased as desired. For example, at the upper extremity of the bed shown, the part 3 has greater pitch than the part therebelow, 20 and the motion of ash relative to that of the cone 25 will be greatly accelerated as the ash moves onto the part 3.

What I claim is:

1. The method of burning solid fuel in the form of particles which may be too great to be carried by a stream of air, comprising supporting said fuel exposed to a controlled volume of air for combustion, and maintaining said supported fuel, during its combustion, in motion about an axis 40 at a high speed, both absolute and relative to said volume of air. 35

2. In a furnace, a conical upwardly divergent fuel-carrying wall, means for feeding fuel upwardly to the apex part of said wall, means for 45 rotating said wall about its conical axis to cause said fuel to be advanced by centrifugal force toward the large end of said wall slowly enough to permit substantially complete combustion during said advance, and means for delivering air 50 for said combustion downwardly toward the apex part of said wall and outwardly toward said wall.

3. In a furnace, a conical upwardly divergent fuel-carrying wall, means for feeding fuel to the apex part of said wall, means independent of 55 said fuel-feeding means, for rotating said wall about its conical axis at sufficient speed to cause said fuel to be advanced by centrifugal force toward the large end of said wall, and means providing for combustion of said fuel during its said 60 advancement and including means for delivering air adjacent said apex part, in radial directions.

HENRI G. CHATAIN.
